UNITED STATES PATENT OFFICE.

LEE T. ALTON, OF BROOKLYN, NEW YORK.

DESIGN FOR A GAS-BURNER OR SIMILAR ARTICLE.

SPECIFICATION forming part of Design No. 34,250, dated March 19, 1901.

Application filed January 19, 1901. Serial No. 43,953. Term of patent 7 years.

To all whom it may concern:

Be it known that I, LEE T. ALTON, a citizen of the United States, and a resident of the city of New York, borough of Brooklyn, 5 county of Kings, and State of New York, have invented and produced a new and original Design for Gas-Burners or Similar Articles, of which the following is a specification.

My invention relates to a new and original 10 design for a gas-burner and similar articles; and it consists in the configuration and correlative arrangement of parts substantially as herein illustrated and described.

In the drawings forming part of this specification, Figure 1 is a plan view of a gas-burner made in accordance with my invention, and Fig. 2 is a perspective elevation thereof.

The central portion of the burner comprises 20 a four-sided body 1, having circular faces 2, the conoidal part 3 superposed thereon, and a part 4 extending laterally upon the conoidal part 3, the four-sided part 1 being connected by a circular piece 5.

From the faces 2 of the four-sided part 1 25 radiate cylindrical arms 6, and from the outer ends of which arms extend square-shaped parts 7, having upwardly-extending tubular projections 8. From the parts 7 extend flat arms 9, having upturned ends 10.

Extending upwardly from the part 4 are 30 two tubular-shaped parts 11 and 12, the latter being of smaller diameter and being surmounted by an annular ring 13.

From the part 3 extends a globular-headed 35 part 14, from which depends a looped part 16.

Having described my invention, I claim—

The design for a gas-burner or similar article substantially as herein shown and described.

Signed at the city, county, and State of New 40 York, this 7th day of January, 1901.

LEE T. ALTON.
